(57) **CLAIM**

The ornamental design for a transparent tire gauge, as shown.

DESCRIPTION

FIG. 1 is a front elevational view of a transparent tire gauge mountable onto a valve stem while checking air pressure in a tire showing my design in a closed position;

FIG. 2 is a front elevational view thereof in an open position;

FIG. 3 is a rear elevational view thereof in a closed position;

FIG. 4 is a rear elevational view thereof in an open position;

FIG. 5 is a left side elevational view thereof;

FIG. 6 is a right side elevational view thereof;

FIG. 7 is a top plan view thereof; and,

FIG. 8 is a bottom plan view thereof.
